ELECTRIC ARC LAMP

George E. Inman, Cleveland Heights, and Eugene Lemmers, Cleveland, Ohio, assignors to General Electric Company, a corporation of New York

Application January 3, 1934, Serial No. 705,048

7 Claims. (Cl. 176—122)

Our invention relates to electric arc lamps of the type comprising refractory metal electrodes sealed in a transparent or translucent bulb or other container. Our invention may be applied 5 to arc lamps of the type disclosed in our pending application Serial No. 618,894, filed June 23, 1932. The lamp disclosed in our pending application consists of a bulb filled with a readily ionizable gas, such as argon or neon, and contains a pair 10 of special electrodes and a resistance heater. The said heater comprises a coil of refractory wire, connected in series with the arc gap and encased in a refractory and insulating tube which extends in heat conductive relation to a body of a vaporizable metallic substance, such as mercury or sodium, in the bulb. The electrodes each comprise a surface coated with a thermionically active material used in combination with a refractory terminal. However, the present invention 15 contemplates the use of electrodes comprising a compact mass of refractory metal impregnated or alloyed with a thermionically active material thus dispensing, if desired, with the refractory terminal, which was used in the electrodes of the 20 said pending application to carry the arc discharge in order to protect the coated surface from disintegration. The said coated surfaces aid in the starting of the arc, wherein a glow or diffuse discharge takes place around the electrodes which 25 concentrates, as the temperature and pressure build up, to an arc, which strikes across the refractory terminals, said terminals being directly in the arc path and closer together than said coated surfaces. The heat from the discharge 30 and the heat radiated from the refractory terminals maintain the coated surfaces in an active condition. The said coated surfaces therefore 35 serve the double purpose of facilitating starting and aiding in the maintenance of the high pressure arc.

One of the objects of our invention is to provide an arc lamp which will be an efficient source of visible and/or ultra-violet rays and which will operate directly from a line carrying the ordinary 45 commercial voltage (approximately 110 volts) without the use of a transformer or other external equipment. Another object is the elimination of a starting electrode by providing novel forms of electrodes or the provision of a novel 50 form of starting electrode to be used with the electrodes described above. Other objects are to insure more positive starting and to maintain more of the active electrode surfaces at the proper temperature. Still another object is the possible 55 elimination of the starting gas in the bulb.

According to the present invention the above-mentioned objects are attained by providing either one or both main electrodes with heater filaments disposed adjacent to the coated surface. In the above-mentioned type of lamp, starting of the arc was sometimes delayed because of a deposit of vaporizable metal on the coated surface. This objection is avoided by the use of the heating elements which vaporize the said vaporizable metal from the coated surfaces and thereby permit access to the active surfaces. In a modified form, the heater element may be provided in an auxiliary starting electrode. Either of these constructions provides more positive starting and more uniform and more nearly 15 correct operating temperature of the active surfaces of the electrodes with a lamp of ordinary design.

Further features and advantages of our invention will appear from the following detailed description of species thereof and from the drawings.

In the drawings, Fig. 1 is an elevation of a form of lamp comprising our invention; Fig. 2 is an elevation at right angles to the view in Fig. 1; Fig. 3 is an elevation, partly in section, of a form of electrode used in our lamp; Fig. 4 is a diagrammatic view of a circuit adaptable for the lamp; Fig. 5 is an elevation, in section, of a modified form of electrode; Fig. 6 is a perspective view of another modified form of electrode; Figs. 7 and 8 are elevations, at right angles to each other, of a modified form of lamp employing an auxiliary starting electrode; Fig. 9 is an elevation, in section, of a form of starting electrode; Fig. 10 is an elevation, in section, of one of the main electrodes of the lamp shown in Figs. 7 and 8; and Fig. 11 is a diagrammatic view of a circuit adaptable for the modified lamp of Figs. 7 and 8.

Referring to Figs. 1 and 2, the lamp comprises a base 10 and a bulb 11 which may or may not be filled with a readily ionizable gas such as argon or neon. A pair of combination electrodes 12 are located in said bulb. The said electrodes are identical in structure and one of them is illustrated in detail in Fig. 3. Each of the electrodes 12 comprises a metal member such as a tube 13 (Fig. 3) preferably of nickel. The said tube 13 is mounted at one end on an insulating collar 14 which is mounted on a conductor 15 at its end which is located just beyond the edge of said tube 13. Instead of the tube 13 a disc or cup, or a compact mass of material having a surface which will easily emit electrons, may also

be used. The said tube 13 has a coating 17 of a thermionically active compound, preferably an alkaline earth metal compound such as barium oxide, on the surface thereof. In the form of electrode shown in Fig. 3, the coating 17 is impregnated in the turns of a helically wound coil 18 disposed on the inner surface of said tube 13. The said tube 13 is electrically connected to the conductor 15 by conductive straps 19. An insulating tube 20 is disposed around the tube 13 and a heating element 21 is wound around said tube 20 and is covered with insulating cement 22. The heater 21 may be incorporated in only one of the electrodes, either upper or lower, if desired. The tube 13 may also be made of tungsten, molybdenum or "Kone" metal, and in addition to barium oxide, the coating thereon may comprise strontium or calcium oxides or combinations thereof.

20 The conductor 15 of upper electrode 12 is connected to a leading-in wire 23 which is sealed in the press portion 24 of a stem tube 25. The conductor 15 of lower electrode 12 is mounted on a cross support wire 26 which is mounted on 25 outwardly extending portions 27 and 28' of a wire 29 which is coiled about a refractory insulating tube 30. The end portion 27 of the wire 29 is connected to a conductor 28 which is covered with an insulating tube 31 and an insulating covering 31' and extends through the stem press 24. A heater comprising a coil 32, preferably of tungsten or nichrome, extends through the tube 30 and is mounted on the inner end of conductor 33 and leading-in wire 34 which extend through 35 the stem press 24. The said tube 30 is preferably of beryllium oxide and is formed into substantially a U shape, the legs of the U extending along the gap between the electrodes and the bent portion passing between the lower electrode 40 12 and the end of the bulb 11. The said bent portion of tube 30 passes adjacent to, or preferably through, a tool of vaporizable metal such as mercury 35 located in the bulb 11. The inner end of a conductor 36 which is covered by an insulating tube 37 is embedded in an insulating bead 38 which is mounted on the outwardly extending portion 28' of wire 29. The opposite end of lead wire 37 is connected to a support wire 39 one end of which is embedded in the stem press 45 24. One end of each of the heating elements 21 of electrodes 12 is connected to the tubes 13 while the opposite ends are each connected to conductor 36.

The tube 30 is heated to luminescence by the 55 heater 32 thus increasing the vaporization of mercury from the pool 35 and greatly increasing the concentration of mercury vapor in the region of the arc which is located directly over the heated pool. The ultra-violet efficiency increases rapidly with increasing mercury vapor 60 concentration. The inner ends of conductor 33 and leading-in wire 34 are disposed in short glass tubes 40 and 41 extending from the stem press 24 and insulating tubes 42—43 are disposed about 65 the said tubes 40—41 and the ends of tube 30 thereby preventing the formation of an arc at 70 said lead wires. Although beryllium oxide is to be preferred for the tube 30, other refractory substances may be used such as thoria, alumina or magnesia.

Referring to Fig. 4, one circuit for the lamp is from lead wire 23 through conductor 15 of upper electrode 12, tube 13, through the heating element 21, conductor 36, heating element 21 of 75 lower electrode 12, tube 13, conductor 15, con-

ductors 26, 27, 28, and 33, heater 32 and lead wire 34. The lead wires 23 and 34 are connected to respective terminal elements in the base 10.

At the start of the operation of the lamp a glow discharge takes place around the upper and lower electrodes 12. Said discharges increase in size and strength as the temperature and pressure build up within the lamp until an arc discharge is formed which strikes across terminals 16 since they are closer together than the tubes 10 13. When the arc is formed the greater amount of current goes through the arc and only a small amount through the heating elements 21.

An auxiliary starting point may be provided adjacent the electrodes 12 to insure easier starting. The said starting points are provided by wires 43' mounted on conductor 36, the ends of said wires extending adjacent the edges of tubes 15 13 of said electrodes 12. The said wires 43' thus provide short gaps to the main electrodes so that discharges are formed therebetween which subsequently transfer directly across the main electrodes 12.

Fig. 5 shows a modified form of electrode 44 in which the heater 45 is located inside of the 25 tube 46. The said tube 46 is mounted at one end on insulating collar 47 which is mounted on a conductor 48. The conductor 48 is preferably of tungsten and has a terminal 49 at the end thereof which extends just beyond the edge of 30 tube 46. An insulating tube 50 surrounds the conductor 48 and the heater 45 is wound therearound and has a coating 51 of insulating cement thereon. A thermionically active material 52 is disposed in the turns of a helically wound coil 35 53 which is located in the tube 46. The tube 46 is connected by conductive straps 54 to the conductor 48 and one end of the heater 51 is connected to conductor 48.

Fig. 6 shows another modified electrode comprising a heater 55' embedded in a hollow cylindrical mass of insulating cement 56' in which is disposed a length of refractory metal screen 57' which is impregnated with a thermionically active material and is rolled into a compact cylindrical mass. A conductor 58' is electrically connected to the metal mass 57'. The outer edge of the said metal mass 57' is able to withstand the effects of the arc discharge while the thermionically active material within the mass continues to emit electrons. An alloy, such as a nickel-barium alloy, may be used instead of the impregnated screen 57'. Also a refractory terminal ball, such as the ball 16, may be used in conjunction with this type of electrode.

Figs. 7 and 8 show a modified form of lamp employing a heated auxiliary starting electrode. The lamp comprises a base 55 and a bulb 56 which may or may not be filled with a readily ionizable gas such as argon or neon. A pair of 60 combination main electrodes 57 are located in said bulb. The said electrodes each comprise a metal member such as a tube 58 which is mounted at one end on an insulating collar 59. Said collar 59 is mounted on a conductor 60, preferably of tungsten, which has a terminal 61 at the end thereof. The tube 58 is connected by conductive straps 62 to conductors 60. A coating 63 of thermionically active material is disposed on the surface of said tube 58, the drawings showing 70 said coating on the inner surface of the tube although it may also be applied to the outer surface. Of course electrodes of the type shown in Fig. 6 may be substituted for electrodes 57.

Conductor 60 of upper electrode 57 is connected 75

to a leading-in wire 64 which extends through the press portion 65 of a stem tube 66. The conductor 60 of lower electrode 57 is mounted on one end of conductor 67 which is coiled about a refractory insulating tube 68. The opposite end of conductor 67 is connected to a conductor 69 which has an insulating tube 10 and an insulating covering 10' thereon and which extends through the stem press 65. A heater 71 is mounted on the ends of a conductor 72 and a leading-in wire 73 and extends through the tube 68 which preferably consists of beryllium oxide, and extends in heat conductive relation to a pool of vaporizable metal 73', said metal being mercury when using the lamp as a source of ultra-violet light. The inner ends of conductor 72 and lead wire 73 are surrounded by short glass tubes 74-75 which extend from the stem press 65. The tubes 74-75 and the ends of tube 68 are covered by insulating tubes 76-77.

Starting electrode 78 is disposed adjacent the upper electrode 57 in the drawings, although it may be placed adjacent the other electrode or between the two main electrodes. The said electrode 78 comprises a metal tube 79 (Fig. 9) mounted at one end on an insulating collar 80 which is mounted on a conductor 81. The said tube 79 is electrically connected to said conductor 81 by a strap 81'. A quantity of thermionically active material 82 is coated on the outer surface of tube 79. An insulating tube 83 is disposed within the tube 79 and a heating element 84 is disposed in said tube 83. One end of heater 84 is connected to conductor 81 and the other end is connected to a conductor 85. Conductor 81 is mounted on a conductor 86 which extends through the stem press 65 and is connected through a resistance 87 in the base 55 to conductor 69. Conductor 85 extends through stem press 65 and is connected through a resistance 88 to lead wire 64.

Referring to Fig. 11, the main circuit is from lead wire 73 through heater 71, conductor 72, conductor 69, conductor 67, lower electrode 57, across the gap to upper electrode 57 and lead wire 64. The starting electrode circuit, comprising resistance 88, conductor 85, heater 84, conductors 81 and 86 and resistance 87, is arranged in multiple with the arc gap, across lead wire 64 and conductor 69.

At the start of this device a glow discharge takes place between the auxiliary electrode 78 and tube 58 of upper electrode 57 and a second glow discharge takes place around the lower electrode tube 58. The said discharges increase in size and strength as the temperature and pressure build up within the lamp until an arc discharge is formed which strikes across terminals 61 of the electrodes since they are closer together than the tubes 58. When the arc is formed the resistances 87 and 88 and auxiliary electrode 78 are substantially cut out of the circuit, practically all the current going through the arc.

What we claim as new and desire to secure by Letters Patent of the United States, is:

1. An electric lamp of the high pressure concentrated arc type comprising a single glass bulb, a pair of electrodes in said bulb each comprising a metal portion having a coating of a thermionically active material thereon and defining a positive-column-path therebetween a separate concentrated refractory metal terminal body of substantial heat capacity mounted adjacent to, and projecting beyond and spaced from the end of, said coated metal portion, and a heating element

adjacent at least one of said coated metal portions, said electrodes being so disposed that said terminal bodies are closer together than said coated metal portions, a quantity of vaporizable metal in said bulb, and a resistance element having a covering of refractory insulating material extending in heat conductive relation to said vaporizable metal. 5

2. An electric lamp of the high pressure concentrated arc type comprising a single glass bulb, 10 a pair of electrodes in said bulb each comprising a metal portion having a coating of a thermionically active material thereon and defining a positive-column-path therebetween, a separate concentrated refractory metal terminal body of substantial heat capacity mounted adjacent to, and projecting beyond and spaced from the end of, said coated metal portion, and a heating element 15 adjacent at least one of said coated metal portions, said electrodes being so disposed that said terminal bodies are closer together than said coated metal portions, a quantity of vaporizable metal in said bulb, and a resistance element in series with the arc gap between said electrodes having a covering of refractory insulating material 20 extending in heat conductive relation to said vaporizable metal. 25

3. An electric lamp of the high pressure concentrated arc type comprising a single glass bulb, 30 a pair of electrodes in said bulb each comprising a metal portion having a coating of a thermionically active material thereon, and defining a positive-column-path therebetween, a separate concentrated refractory metal terminal body of substantial heat capacity mounted adjacent to, 35 and projecting beyond and spaced from the end of, said coated metal portion, and a heating element adjacent each of said coated metal portions, said heating elements being connected in series and said electrodes being so disposed that 40 said terminal bodies are closer together than said coated metal portions, a quantity of vaporizable metal in said bulb, and a resistance element in series with the arc gap between said electrodes having a covering of refractory insulating material 45 extending in heat conductive relation to said vaporizable metal. 50

4. An enclosed arc device comprising a bulb, refractory metal main electrodes in said bulb, a coating of a thermionically active material on said electrodes, a resistance in series with the arc gap between said electrodes, and an auxiliary starting electrode in said bulb, said auxiliary electrode comprising a metal portion having a coating of thermionically active material and a heating element 55 adjacent said coated metal portion and electrically connected in multiple with said main electrodes. 55

5. An enclosed arc device comprising a bulb, refractory metal main electrodes in said bulb, a 60 coating of a thermionically active material on said electrodes, and an auxiliary starting electrode in said bulb, said auxiliary electrode comprising a metal portion having a coating of thermionically active material and a heating element 65 adjacent said coated metal portion and electrically connected in multiple with said electrodes. 65

6. An enclosed arc device comprising a bulb, a pair of electrodes in said bulb each comprising a metal portion having a coating of a thermionically active material thereon, and a separate concentrated refractory metal terminal body of substantial heat capacity mounted adjacent to, and projecting beyond, said coated metal portion, 70 75

- 5 said electrodes being so disposed that said terminal bodies are closer together than said coated metal portions, a quantity of vaporizable metal in said bulb, a resistance element having a covering of refractory insulating material extending in heat conductive relation to said vaporizable metal, and an auxiliary electrode in said bulb, said auxiliary electrode comprising a metal portion having a coating of thermionically active material 10 and a heating element adjacent said coated metal portion.
- 6 7. An enclosed arc device comprising a bulb, a quantity of vaporizable metal in said bulb, a pair of spaced refractory metal electrodes in said bulb defining therebetween a positive-column-path 15 and having a coating of thermionically active

5 material thereon, a ballast resistance heater in said bulb in series with the arc gap between said electrodes, said ballast resistance heater being substantially U-shaped and having a covering of refractory insulating material thereon, the legs of said U extending along the arc gap between said electrodes on opposite sides thereof and the connecting portion of said legs extending in heat conductive relation to said vaporizable metal, and a heating element adjacent at least one of said 10 electrodes, said electrodes being so disposed that the arc gap therebetween extends longitudinally of said bulb and in the path of vapors volatilized from said vaporizable metal.
